REPAIR OF BROKEN LIGHTING FILAMENTS

George R. Borden, Jr., Blaine, Wash.

Application March 6, 1943, Serial No. 478,286

4 Claims. (Cl. 176—7)

This invention relates to the art of repairing broken filaments of electric light globes, and for its general object aims to provide a heat-responsive method of repairing the break particularly characterized in that the same permits the ends of the break to be electrically connected without fusing the filament wire.

It is here pointed out that the present method, in common with the method of Charles J. Sellander described in his U. S. Pat. No. 2,034,960 of March 24, 1936, is one which, without effecting the sealed condition of the lamp, subjects the interior structure to the heating influence of a stepped-up voltage adapted to serve a fusing office. There is this difference, however. The method of the patent essentially places the filament under an intensity of heat which is destructive thereto, while my method requires and uses an appreciably lower voltage developing a heat well below critical. To better understand the salient distinction between the two procedures, it is desirable to somewhat cursorily consider both procedures and by way of comparison point out that the invention the patent resides in a method functional to accomplish the repair by bringing the broken filament ends into contiguity and fusing together to present a conglomerate bead, necessarily demanding that the potential used for the fusing step develop a temperature condition at or above the melting point of the filament. While the fusing potential is most destructive to the filament life at the actual point of fusing and the crystallization which occurs may be confined to the one spot, it becomes self-evident that any crystallization of the filament with the resulting spot-loading in use will cause the filament to again burn out within a relatively short period of time. Excepting as a temporary expedient finding acceptance, perhaps, under conditions of a national emergency when materials are scarce and only a limited quantity of new bulbs are made available to civilian users, the method of the patent is therefor of questionable value.

My method, on the other hand, and looking to an elimination of said objectionable fusing of the filament metal, recognizes the presence within the bulb of an electrically-conductive metal having a fusing point very appreciably below that of the filament and which, applied as a bridge across the broken ends of the filament, functions effectively to close the filament circuit, the metal in question being that which composes the terminal posts and intermediary spiders which support the filament. It may be pointed out, relative to the test line, that the circuit is completed by the in-

strumentality of closing the globe filament button and also placing the main switch such that contact is had between the center posts and the two terminals marked A. C. Tracing the wire which leads from the lower side of the plug-in element, it will thus be seen that this side of the plug is brought into direct connection with one of the two terminals of the mogul socket, and that a circuit is completed from the other terminal of the mogul socket through the globe filament button and the globe rheostat back to the other side of the plug-in element, the current in consequence of taking the course of least resistance traversing the globe rheostat line rather than entering the A. C. transformer unit, the step-up side of the latter being isolated, moreover, by the fact of the voltage regulating switches being open. Resorting, therefor, to a bridging of the gap by the use of such available metal having a comparatively low fusing point and high electric conductivity, I accomplish, in addition to safeguarding the filament against the deleterious effects of a crystallizing heat, the further and important advantage of maintaining very close to the exact lighting efficiency for which the bulb was manufactured.

There is a still further advantage attained from my bridging procedure and which assures an extended period of usage even with lamps which, due to a momentary arcing across the gap at the time of the break, had developed spot temperatures sufficiently high to have caused crystallization at the extreme tips of the broken ends. Appreciating that my bridging metal in the course of being fused across the gap will most usually encase the end extremities, current which is thereafter passed through the filament is relatively isolated from the extreme tips in that, following the course of least resistance, the same passes from the filament to the bridge at a point removed, if only slightly, from such tips. It becomes self-evident, therefore, that being enabled to by-pass a known point of weakness and utilizing, for the by-pass, a metal of comparatively low resistance to electric current, the generated heat is comparatively lower in the immediate neighborhood of the break.

As a means of most efficiently practicing the process, the invention further aims to provide a machine—electrical in nature—which is capable of being used either with direct or alternating current.

Further objects and advantages will appear in the course of the following description and claims, the invention consisting in the new method of

repairing burnt-out filaments and in the novel construction, adaptation and combination of parts for practicing the method, all of which will be set forth with particularity in the following description and in the claims thereto annexed.

In the accompanying drawing:

Figure 1, as a wiring diagram, illustrates the now preferred embodiment of a machine for performing my repair technique; and

Fig. 2 represents a stand-wire assembly of a conventional electric lamp and indicates a lighting filament supported thereby and which has been repaired in accordance with the invention, the glass bulb having been deleted for purposes of maximum clarity in the illustration.

The electric circuits, one A. C. and the other D. C., which I provide in my machine are believed to be readily traced without numerical reference to the various parts employed, these parts being identified by symbol and each performing their usual function. Novelty is claimed only in the sense of combining the parts in a particular manner to accomplish the specific end of supplying current of controlled intensity to a mogul socket into which the bulb to be repaired is screwed, the intensity in the instance of the A. C. circuit being governed by regulating switches—indicated as four in number—joined at four tap points to the high-voltage transformer, and in the D. C. circuit being governed by a rheostat embodied in a related direct current transformer unit. The wiring hook-up also includes a test line which, as can be seen from the drawing, includes a modifying rheostat and a circuit-closing switch arranged to be employed, after a repair operation, to pass line current through the filament.

The electric lamp to which the method of the present invention is adapted is of the usual construction providing an assembly of stand wires supporting the filament upon the upper extremities thereof. In the instance of some low-watt lamps, only two such stand wires are provided, one operating as one and the other as the other of the two terminal posts for the filament, the latter being carried from the upper end of one post directly to the other post. The two terminal posts are composed of an electrically conductive material having a fusing point below the fusing point of the filament. In the instance of high-watt lamps, the terminal posts are customarily augmented by one or more spider arms which have their lower ends anchored by embedding the same in a glass rod, the said spider arms being similarly electrically conductive with a fusing point below the fusing point of the filament. Insulated one from another and from the terminal posts, these spider arms extending upwardly from the supporting rod and usually terminate at the upper ends in loops which are caused to lie at spaced intervals within a relative horse-shoe curve of which the end extremities are occupied by the upper ends of the terminal posts. The filament, in lamps having the said spider arms in addition to the terminal posts, is strung successively through the loops of the spider arms from one to the other terminal post.

Now describing the repair procedure, the lamp is first examined toward ascertaining the standing wire which is deemed most desirable as a bridging piece, which is to say that the operator selects the terminal post or spider arm which most readily lends itself to the repair and which most usually will be that post or spider arm lying in the closest proximity to the break. Having screwed the lamp into the mogul socket—a re-

ducing insert being employed where a smaller lamp base requires such—the operator closes the main switch to complete either an A. C. or a D. C. circuit, according to the source of energy

used, and passes a high-voltage current into the lamp sufficient to cause a jump-spark across the lower ends of the terminal posts. From an inspection of the drawing, Fig. 1, it will be seen that two lines lead to the two terminals of the mogul socket, and that the jump-spark consequently results within the lamp being repaired whether using the A. C. or the D. C. high-potential circuit as the potential is caused to be stepped-up by the A. C. hi-voltage transformer or the D. C. hi-voltage transformer, as the case may be, and which are each operatively joined to these two lines. The effective intensity of the stepped-up potential is regulated in the instance of the A. C. current by the indicated and selectively used voltage-regulating switches, and in the instance of the D. C. circuit by the rheostat built into the D. C. transformer, said A. C. and D. C. hi-voltage circuits being caused to be selectively closed through the use of the main switch which is indicated as being of a two-way knife character movable to the left for closing the A. C. circuit and movable to the right for closing the D. C. circuit, the globe filament button being open to isolate the test-line by-pass. As the heat rises within the lamp, the standing pieces are rendered relatively pliable and the operator, either by tapping the bulb or manipulating the mogul socket, causes the selected repair wire to be shifted into such a position as will permit the free end of the broken filament to touch the same. As contact occurs, and bearing in mind that the other end of the filament break will be in touching relation to the shifted spider arm as it rides in the loop of the latter, the high-voltage current makes a circuit through the filament and the bridging piece of the repair wire. The voltage can be now regulated, according to the cross-section of the bridging metal, to readily fuse the latter without, however, being sufficiently high to develop crystallization within the filament. Repairs are most usually made with the spider arms rather than the terminal posts in that the majority of breaks are found to occur at mid-points as distinguished from the ends of the filament. However, even with the larger cross-section which is characteristic of the terminal posts, the same will fuse under a temperature condition very appreciably below that which will melt the filament.

In Fig. 2 I have illustrated one example of a repair operation in which the upper extremity *s'* of a spider arm *s* has been fused as a bridge to connect the broken ends *f'* and *f''* of the filament *f*, the end *f'* in such instance having been the part of the filament carried in the loop of the spider arm and the end *f''*, being the free end, having been caused to contact the spider arm at a point somewhat below the loop. The loop itself conglomerates by the fusing heat to form a part of the bridge. To further identify the parts shown in this view, the two terminal posts of the stand-wire assembly and which supply current to the filament are denoted by *p'* and *p''*, and the glass rod with its surmounting head and into which the root ends of the spider arms are embedded is designated by *a*.

The method of my invention and structure suitable for practicing the same is thought to be clear from the foregoing taken with the accompanying drawing.

What I claim, is:

1. The described machine functioning through the instrumentality of a stepped-up potential to repair a break in the filament of an electric lamp: comprising the combination of two normally incomplete electric circuits, one A. C. and the other D. C. arranged to be selectively energized by standard line current and each including, with a transformer unit to perform the step-up office of the machine, a modifying voltage regulator and a switch for closing the respective circuits; a tail socket, common to both circuits, for the reception of the lamp to be repaired; and a normally open low-potential test circuit providing a circuit-closing switch and having functional connection with the lamp socket.

2. The structure of claim 1 having a pilot light common to each of the said circuits and subject to the low-potential of the line energy.

3. The method of repairing a broken filament in an electric lamp of the described character, which is to say a lamp providing an assembly of stand wires including the two terminal posts for the lamp and which wires are disposed in spaced relation with the filament supported by the upper extremities thereof, the wires being of an electrically conductive nature insulated one from another and having a fusing point below the fusing point of the filament, said method consisting in obtaining a contact closure of the filament circuit by selecting one said stand wire proximate

5 to the break and bringing a part of such selected wire into bridging relation to the break, and then placing a potential on the terminal posts sufficiently high to fuse the bridge as an integral part of the circuit without reaching the fusing point of the filament.

10 4. The method of repairing a broken filament in an electric lamp of the described character, which is to say a lamp providing an assembly of stand wires including the two terminal posts for the lamp and one or more spider arms lying in intervening relation between the terminal posts and wherein the filament is supported by the upper extremities of said stand wires in its carry from one to the other of the terminal posts, said stand wires being of an electrically conductive nature insulated one from another and having a fusing point below the fusing point of the filament, the method consisting in placing a high-voltage load upon the terminal posts of the stand assembly to effectuate an arc discharge within the lamp rendering the stand wires pliable and then, selecting the stand wire most proximate to the break, manipulating the lamp to cause a portion of the selected wire to bridge itself across the break, the impressed potential which now traverses the filament being held to an intensity sufficient to fuse the bridge as an integral part of the filament circuit without reaching the fusing point of the filament itself.

CERTIFICATE OF CORRECTION.

Patent No. 2,528,187.

August 31, 1943.

GEORGE R. BORDEN, JR.

It is hereby certified that error appears in the printed specification of the above numbered patent requiring correction as follows: Page 1, first column, line 54, beginning with "It may be pointed out," strike out all to and including "open." in line 18, same page, second column, and insert the same after "filament." on page 2, first column, line 36; page 2, first column, line 57, for "extending" read --extend--; and second column, line 27, after "closing" strike out "the"; page 3, second column, line 26, claim 4, for "potenial" read --potential--; and that the said Letters Patent should be read with this correction therein that the same may conform to the record of the case in the Patent Office.

Signed and sealed this 26th day of October, A. D. 1943.

(Seal)

Henry Van Arsdale,
Acting Commissioner of Patents.
